FLEXIBLE DISPENSING BOTTLE

Fred T. Pickerell, Red Bank, Edward M. Wixted, Weehawken, and John J. Graham, Jr., Bound Brook, N. J., assignors to Schering Corporation, Bloomfield, N. J., a corporation of New Jersey

Application May 5, 1958, Serial No. 50,746

Term of patent 14 years

(Cl. D58—6)

Fig. 1 is a front elevational view of a flexible dispensing bottle, showing my new design;

Fig. 2 is an end elevational view thereof;

Fig. 3 is a top plan view thereof;

Fig. 4 is a bottom plan view thereof;

Fig. 5 is a vertical sectional view thereof taken on the line 5—5 of Fig. 2; and

Fig. 6 is an exploded view thereof.

We claim:

The ornamental design for a flexible dispensing bottle, substantially as shown.
